UNITED STATES PATENT OFFICE.

CANNON H. FLEMING, OF RICHMOND, VIRGINIA.

DESIGN FOR A STOVE.

SPECIFICATION forming part of Design No. 36,148, dated November 25, 1902.

Application filed October 22, 1902. Serial No. 128,353. Term of patent 7 years.

To all whom it may concern:

Be it known that I, CANNON H. FLEMING, a citizen of the United States, residing at Richmond, in the county of Henrico and State of Virginia, have invented and produced a new, ornamental, and original Design for a Stove; and I do hereby declare the following to be a full, clear, and exact description of the same, reference being had to the accompanying drawing, forming a part thereof.

My design is for a stove, as illustrated in the accompanying drawing.

The same consists of a cylindrical body portion A, having upon it a fancy scrollwork C. At the outer edge of the cylindrical body portion A is a rim or flange D, having fancy scrollwork thereon, and at the lower end of said cylindrical body portion is a rim or flange E, also having fancy scrollwork thereon. Four support-legs F, having fancy scrollwork thereon, are shown, and extending between the legs and from the upper ends thereof are two curved foot-rests G.

The cylindrical body portion A of the stove is crowned with a cap H, having fancy scroll-work thereon, and projecting outwardly from the cap appears a fancy knob I, which consists of pedestal i and a fluted wall-shaped configuration i' and a flat fancy open-work piece i'', projecting outwardly therefrom. A circular stovepipe-opening J appears at one side of the cap.

Having described my design, what I claim as new, and desire to secure by Letters Patent, is—

The ornamental design for a stove substantially as herein shown and described.

In testimony whereof I hereunto affix my signature in presence of two witnesses.

CANNON H. FLEMING.
